INSTRUMENT BOARD FOR STOVES

John C. Rogers, Cicero, Ill., assignor to Crown
Stove Works, Cicero, Ill., a corporation of Il-
linois

Application February 3, 1936, Serial No. 62,125

3 Claims. (Cl. 126—214)

This invention relates to the general art of cooking stoves and ranges, and has reference more particularly to the mounting of the various gas or electric controls, time indicators and signals, heat regulators, lamps and similar accessories with which modern stoves and ranges are equipped.

Modern cooking stoves and ranges usually have a low wall or so-called "fence" on the rear edge of the stove top. It is very desirable to permanently mount the several manual controls, such as heat indicators, heat regulators, timers, lamps and other instruments on this fence where they are in full sight, within easy reach, and are unaffected by the heat of the burners. Some stoves are equipped with a single instrument, such as an oven heat regulator, a clock control and indicator which is set to determine the time of starting the heat and its duration of application, an automatic gas shut-off that prevents over-cooking or burning, etc. Others are equipped with two such devices, and still others with three or more. This has required a special instrument board or fence for each stove to fit each customer's order.

It has heretofore been known in the art of instrument boards for automobiles to form an opening in the instrument board, and to mount in such opening a detachable panel carrying a number of indicating and control instruments. One object of the present invention has been to simplify the construction and reduce the cost of stoves and ranges by applying this broad principle in the manufacture of stoves and ranges, which would permit the use of a single standard instrument board or fence for all stoves and ranges of a given width, the differences in the number and kinds of instruments called for by different customers' orders being taken care of by the panel equipment.

Other objects of the invention are to provide, in association with a panel plate for use on a stove fence as above described, improved means for assembling and mounting a number of control instruments and other accessories, such as are hereinafter described and claimed, on or in association with the panel plate.

An approved embodiment of this invention is illustrated in the accompanying drawings in

50 which:

Fig. 1 is a front elevation of an illustrative embodiment of the improvement.

Fig. 2 is an enlarged horizontal section on the line 2—2 of Fig. 1.

55 Fig. 3 is an enlarged front elevation of the

panel plate showing three control instruments thereon.

Fig. 4 is an enlarged rear elevation of the parts appearing in Fig. 1.

Fig. 5 is a vertical section on the line 5—5 of 5 Fig. 4.

Figs. 6 and 7 are enlarged horizontal sections on the lines 6—6 and 7—7 respectively of Fig. 4.

Referring to the drawings, 10 designates the top of a cooking stove or range, on the rear edge of 10 which is mounted the low rear wall or fence 11 hereinabove mentioned. As best shown in Figs. 2 and 4, the fence 11 is formed with a countersunk opening preferably centrally thereof, bordered by a marginal seat 12 which receives a flat preferably cast metal panel plate 13, said panel lying substantially in the vertical plane of the fence 11.

In the upper portion of the panel 13 is an opening 14 which, as indicated by dotted lines in Fig. 4, is of square form with rounded corners, 20 and through this opening extends the face portion 15 of an electric clock. The body or barrel portion 16 of the clock abuts against the rear side of the panel 13, as shown in Fig. 4, and is secured in place by means hereinafter described. 25 The face portion of the clock 15 includes the usual dial face and second, minute and hour hands, and associated therewith is a rotatable timer disc 17 graduated in minutes, which disc may be manually set, as by a knob 18 geared thereto to indicate 30 a cooking period of any desired number of minutes, at the expiration of which a bell or other signal is sounded to indicate to the cook that the proper cooking period has elapsed. Another knob 19 is geared to the clock train to set the hands 35 of the clock. Electric clocks of this type are a well known article, and hence further illustration and description thereof is not deemed necessary.

Below and to either side of the opening 14 are 40 round openings 20 and 21 bordered on the front side of the panel by protuberant rims 22 and 23 respectively. Projecting through the opening 20 is an oven heat regulator 24, the face of which is suitably calibrated in degrees of heat. The 45 casing 25 of this regulator is mounted on an inverted U-shaped pipe fitting 26 (Fig. 4) in turn supported on a pair of pipes 27 and 28, one of which communicates with the gas manifold and the other with the oven burner. In the casing 25 50 is a valve manipulated by a knob 29 on the face of the regulator, which controls the amount of gas flowing to the burner.

Through the hole 21 projects an electric socket member 30 having fast on its rear end behind the 55

panel 13 a double ended socket 31 adapted to receive the plug 32 of a lead 33 extending into the electric clock, and also a plug 34 of a lead 35 that leads to an electric lamp 36. This lamp 36 is mounted in a hood 37 in turn mounted on the upper end of a standard 38. As shown in Fig. 5, the standard 38 is formed with a crimp or offset 39 that rests on the top edge of the fence 11 and below said clamp or offset 39 are a pair 10 of depending legs 40 that, as shown in Fig. 4, straddle the upper portion of the clock barrel 16. The legs 40 are slotted on their inner edges as shown at 41 in Figs. 4 and 6, and these slotted portions lie in contact with low tapped bosses 42 15 on the rear face of the panel 13. Screws 43 extend through the slots 41 and into the tapped holes of the bosses 42, thereby securely clamping the standard 38 on the panel 13.

Referring to Figs. 2, 4 and 7, 44 designates a 20 U-shaped bar that extends across the rear end of the barrel 16 and at its ends is secured to the lower ends of the legs 40 by machine screws 45 and nuts 46; the bar 44 manifestly securely locking the clock barrel in place.

25 As shown in Fig. 4, the socket member 31 may be attached to the rear of the panel 13 by a screw 47 extending through an apertured lug 48 on the socket 31 into a tapped hole in the rear of the panel. The socket member 30 on the 30 front face of the panel has been designed for supplying current to a toaster or similar article. The panel 13 is preferably provided on its front with a small panel or plaque 49 which may carry the manufacturer's name, or the stove number, 35 or other data.

The specific structural details herein shown and described may be varied within the spirit and purview of the invention as defined in the following claims.

40 I claim:

1. An instrument board for stoves, comprising a substantially flat vertical fence adapted to be mounted on the rear edge portion of the stove top

and formed with an opening and a countersunk panel seat bordering said opening, an instrument panel of a size and shape to fit said seat and lie substantially in the plane of said fence, means for detachably fastening said panel on said seat, a standard detachably secured to the said panel and extending above said fence and carrying a hood overhanging the stove top and a lamp in said hood. 5

2. An instrument board for stoves, comprising 10 a substantially flat vertical fence adapted to be mounted on the rear edge portion of the stove top and formed with an opening and a countersunk panel seat bordering said opening, an instrument panel of a size and shape to fit said seat and lie substantially in the plane of said fence, 15 said panel having an opening, means for detachably fastening said panel on said seat, an electric clock having a face portion occupying said last named opening and a barrel lying against the 20 rear side of said panel, a standard detachably secured to the rear side of said panel and extending above said fence and carrying a hood overhanging the stove top and an electric lamp in said hood, said standard having a pair of depending legs straddling said barrel, a clamp bar extending across the rear end of said barrel and at its ends attached to said legs, an electric switch mounted on said panel, and leads from said switch to said clock and said lamp. 25

3. An instrument board for stoves, comprising 30 a substantially flat vertical fence adapted to be mounted on an edge portion of a stove top and formed in its front side with a panel seat, an instrument panel of a size and shape to fit said seat, said panel having an opening, means for detachably fastening said panel on said seat, an electric clock and an electric lamp for illuminating said clock both mounted on said panel and an electric socket member serving said clock and lamp mounted on the rear side of said panel and projecting through said opening. 35 40

JOHN C. ROGERS.
